UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPE-WRITING MACHINE.

1,178,190.

Specification of Letters Patent.

Patented Apr. 4, 1916.

Application filed July 21, 1914. Serial No. 852,141.

To all whom it may concern:

Be it known that I, BURNHAM C. STICKNEY, a citizen of the United States, residing in Elizabeth, in the county of Union and State of New Jersey, have invented certain new and useful Improvements in Type-Writing Machines, of which the following is a specification.

This invention relates to ribbon-vibrating mechanism for typewriting machines, and particularly to means for bringing either stripe or color of a bichrome ribbon into use at will.

In the patent to Joerrisen and Livingston, No. 753,797, dated March 1, 1904, the ribbon and the vibrator are bodily shifted up and down to bring the same to different normal positions; and one of the objects of this invention is to provide improved means for effecting such shift.

Another object of my improvements is to reduce or eliminate the liability of the ribbon vibrator to overthrow when the type keys are rapidly operated. To this end, I connect the usual ribbon-vibrating lever to its actuator by means of a link and lever, which swing to or near dead-center when the ribbon is in printing position; the link and lever hence serving as a lock to prevent the momentum of the ribbon vibrator from carrying it too far, which would cause the types to strike partly upon the other stripe, or to "bleed." For bringing the different colors into use at will, I provide a controlling device, preferably in the form of an arm, upon which are pivoted both said ribbon-vibrating lever and also the device by which it is operated. Said controlling arm is mounted to swing upwardly, and carry up said ribbon-vibrating lever and the ribbon carrier itself, together with the ribbon, when it is desired to bring the red stripe of the ribbon into use. The vibrating motion of the ribbon is derived from the key-operated universal bar usually provided in the Underwood typewriter; a vertically slotted yoke being fixed upon the universal-bar frame to engage a ribbon-vibrating wrist which projects from a lever which is connected by a link to the ribbon-vibrating lever proper. The vertical slot in the actuator permits the wrist to play up

and down as the ribbon mechanism is shifted up and down to bring different stripes into use. All of the above-mentioned mechanism, (except the slotted actuator) is mounted on the rocking frame which in the Underwood typewriter shifts the platen up and down to enable the different types to print; and the slot in the above-mentioned actuator accommodates this case-shifting movement. When the ribbon is shifted up to enable the lower or red stripe on the ribbon to become effective, the toggle may not itself operate to arrest the ribbon vibrator; but a separate fixed stop may be provided for this purpose.

Another object of the invention is to effect some reduction in the length of stroke of the ribbon vibrator when the upper color stripe (usually black) is in use, this stripe being the one commonly employed in typewriting. The relation of said levers, and said connecting link, and said controlling arm to the slotted actuator is such that when the parts are in black-writing position, the stroke of the ribbon-vibrating lever may be less than when the parts are in position to write red.

Another object of the invention is to provide ample means for preventing the ribbon from covering the printing point at type strokes when it is desired to write stencils. In carrying out this feature, the ribbon is shifted bodily down so far that, although the ribbon-vibrating mechanism operates at every type stroke, it does not carry the ribbon up far enough to cover the printing point; and the length of stroke of the ribbon vibrator may be even less than when the black stripe is in use, so that, when writing stencils, the vibration of the ribbon at the key strokes will not be objectionable. This shifting of the ribbon to ineffective position is preferably effected by a separate finger-piece from those which control the shifting of the ribbon from black to red.

Other features and advantages will hereinafter appear.

In the accompanying drawings, Figure 1 is a sectional side elevation of parts seen in Fig. 3, but showing the ribbon-vibrating mechanism as shifted or switched down to

idle position, to cause the ribbon to fail to reach the printing point at the type strokes, so that stencils may be written. Fig. 2 is a front elevation to show the connection between the finger-pieces and the shifting arm upon which are carried the ribbon-vibrating levers. In Fig. 2 the parts are shown shifted to the position in which the ribbon will work idly at the key strokes, as in Fig. 10. Fig. 3 is a longitudinal section or elevation taken about centrally of an Underwood typewriting machine, with the present improvements applied thereto. At Figs. 1, 2 and 3 the platen-shifting mechanism of the typewriting machine is in position for writing lower-case or small letters. Fig. 4 is a view similar to Fig. 2, but showing the device set for bringing the red stripe into use; the machine being understood to be in lower-case position. Fig. 5 is a front perspective view of the ribbon-vibrating mechanism and part of the platen-shifting mechanism; the parts being in normal positions, the ribbon mechanism being set for bringing into use the top or black stripe, and the mechanism being set for lower-case. Fig. 6 is a sectional side elevation showing the parts in the same position as at Fig. 5, but with the type in printing position and the ribbon 25 vibrator carried up to interpose the ribbon between the type and the platen. Fig. 7 is a view similar to Fig. 4, but showing the mechanism shifted to cause the ribbon to print black, or to bring the upper stripe 30 into use. Fig. 8 is similar to Fig. 6, but showing the platen shifted to upper-case position; the ribbon mechanism being set for writing black, and being in printing position. Fig. 9 is similar to Fig. 6, but showing the mechanism shifted to bring into use the red or lower stripe of the ribbon; the parts being in normal position, and the platen-shifting mechanism in lower-case position. Fig. 10 is similar to Fig. 9, 45 but showing the type in printing position and the ribbon thrust up to interpose the red or lower stripe between the type and the platen. Fig. 11 is similar to Fig. 10, but showing the platen shifted up to capital 50 position.

The keys 1 are connected to levers 2 and bell-crank 3 to swing type-bars 4 to strike rearwardly against a platen 5, which is mounted on a platen frame 6, the latter 55 shiftable up and down on a carriage 7, which travels on rails 8. The shifting is effected by a special key 9, which is mounted upon a bell crank lever 10, the latter engaging an arm 11 of a shift frame 12, which is fulcrumed at 13 on the framework 14 of the typewriter and comprises brackets or arm 16, united at their front ends by a shift rail 17, upon which runs a roll 18, mounted on the platen frame 6. The carriage is 60 driven by the usual spring barrel, not 65

shown, and has a rack 19 in mesh with a pinion 20, which drives an escapement wheel 21, the latter controlled by dogs 22, which in turn are operated by a frame 23, having on its forward edge a universal bar 24, operated by the heels 25 on the type-bars, and mounted at its rear end on rock arms 26, whereby, at every printing stroke of a type-bar, said universal bar is pressed backwardly, and the carriage is caused to feed; the universal bar being returned by the usual spring 27.

The universal-bar frame is employed to vibrate the ribbon up and down to cover the printing point at the type strokes. For this purpose, there is erected upon the universal bar a yoke 28, which of course moves backwardly with the universal bar during the printing stroke of the type and returns to normal position as the type swings downwardly. This yoke 28 is provided with a vertical slot 29, in which plays a wrist 30, whereby the vibratory movements of the inking ribbon are produced. This wrist projects from an arm 31, extending upwardly from a pivot 32; and said arm 31, taken with arm 33, forms a lever, which by means of the wrist 30 is vibrated at the printing strokes of the type-bars. A link 34 extends from 33 to the lever 35, and lifts 35 the same to elevate the ribbon-carrier 36 to interpose the ribbon between the type and the platen; the lever 35 and the carrier 36 being loosely jointed by means of pin 37 and slot 37^a, as shown.

The ribbon may comprise an upper stripe 38, usually black, and a lower stripe 39, usually red. As shown at Fig. 3, when the upper or black stripe is in use, the ribbon stands a little below the printing line on the platen; but not quite so far as illustrated in said Joerrisen and Livingston patent, so that the stroke of the ribbon when writing black, (which is in use nearly all the time) is somewhat shortened, and hence the speed 105 of operation of the ribbon-vibrating parts is reduced, thus lessening the wear thereon and also reducing or eliminating the liability of overthrow of the ribbon due to weakness and springiness of the parts and 110 looseness of the joints.

The operation of the parts so far described will be apparent, the type key 1 depressing the lever 2 and rocking the bell crank 3 to swing up the type-bar 4; the heel 25 on the latter striking the universal bar 24 and pressing the same backward, together with the ribbon-actuating yoke 28, which, by means of the wrist 30, vibrates the lever 31, 33 to thrust the link 34 forwardly, and thereby swing up the lever 35, together with the carrier 36, to bring the upper or black stripe 38 over the printing point, as at Fig. 6. At the instant that the imprint is being made, it will be seen that 115 120 125 130 135

the arm 33 forms with the link 34 a temporarily straightened toggle; and it will be understood that the ribbon vibrator has hence been brought slowly to rest, and also that the lever 35 is powerless to vibrate the lever 33 beyond the Fig. 6 position, owing to the fact that the three toggle pivots are substantially in a straight line; and hence liability of overthrow of the ribbon is substantially reduced or eliminated. Upon release of the finger-key, the type-bar falls back to normal position, and the spring 27 returns the universal bar, together with the ribbon-vibrating mechanism. The feed of the paper carriage takes place in the usual manner. It will be further observed that said lever 31, 33 is mounted by means of its pivot 32 upon an arm 40, and that said ribbon-vibrating lever 35 is pivoted at 41 to the forward end of the same arm 40; the pivot 32 being in rear of the pivot 41, and the pivot or fulcrum 42 being at the rear end of the arm. This arm 40 is shifted up from the Fig. 6 position to the Fig. 9 position when it is desired to use the red stripe of the ribbon, and, in shifting up, it carries up bodily the lever 35, together with the carrier 36 and the ribbon thereon, so that the upper edge of the ribbon coincides with the lower edge of the line of imprints on the work-sheet, or possibly overlaps said lower edge a trifle, without however hiding so much of the written characters as to render them difficult to read. When a type key is now depressed, the operation takes place which has been already described, the parts moving from the Fig. 9 position to the Fig. 10 position, in which it will be seen that the red or lower stripe covers the printing point when the imprint is made. At this time, the toggle arms 33, 34 are not in line, and do not themselves prevent overthrow of the ribbon; but, if desired, such overthrow can be prevented by means of a stop lug 43 on the lever 35 (Fig. 10) striking against a plate 44, which is fixed upon the platen-shift rail 17.

The movement of the color-controlling arm 40 may be effected by a sliding cam plate 45, supported by means of headed studs 46 upon the rear face of the platen-shift rail 17; said studs passing through horizontal slots 47 in the cam plate or slide, whereby the latter is supported and guided. In said cam plate is a long diagonal slot 48, into which extends a pin 49 formed upon the tip of the shiftable color-controlling arm 40, so that, as the cam plate or slide is thrust endwise, said pin and arm are cammed up and down. The pin 49 may also be guided in a vertical slot 50, formed in said plate 44, which is fixed by screws 51 to the rear face of said platen-shift rail 17 (Figs. 2 and 4); the diagonally slotted end of the slide 45 being confined between the shift-rail and

said vertically slotted plate 44. The slot 50 supports the pin 49 against lateral displacement while it is being cammed up and down by means of the diagonal slot 48 in said slide. Both the slide 45 and the plate 44 70 may be curved concentrically with the pivot 42 of the color-controlling arm 40, as illustrated.

The color-changing movements of the cam-plate or slide 45 are effected by keys 52 75 and 53, provided upon a cross arm 54 at the front of the typewriter, said cross-arm mounted upon the forward end of rock shaft 55, from whose rear end depends a crank 56, having a wrist 57 to engage a vertical 80 slot 58 in an arm 59, the latter formed on and extending downwardly from said cam plate or slide 45. The vertical slots 50 and 58 are long enough to accommodate the up and down shifting movements of the slide 85 45 which occur when the platen-shift rail 17 rises and falls.

The cross arm 54 can be held in any position to which it is set, by means of a detent spring 60, having perforations 61, 62, 63, to 90 engage the point of a beveled pin 64 fixed upon the cross-arm 54. By pressing either of the keys 52 or 53, the ribbon mechanism may be set for bringing into use either the upper stripe or lower stripe of the ribbon 95 at the printing strokes, either key 52 or 53 operating to rock the shaft 55, and by means of the crank 56 to adjust the slide 45 longitudinally of the shift rail 17, and cause the cam slot 48 to cam the pin 49 upwardly or 100 downwardly, together with the color-controlling arm 40, thus carrying up or down the ribbon-vibrating levers 33, 35.

As is the case in said Joerrisen and Livingston patent, the ribbon mechanism shifts 105 up and down bodily together with the platen 5; and the operation of vibrating the ribbon at the type strokes takes place as before, the slot 29 in the ribbon actuator being long enough to accommodate the necessary shift- 110 ing of the wrist 30 at the case-shifting operation.

As has been pointed out, the slide 45, which supports the front end of the color-controlling arm 40, is mounted upon the 115 platen-shift rail 17; and it will also be seen that the rock shaft 42, upon which said arm 40 is fixed, may be journaled at its ends at 65 in the side arms 12 of the rocking frame, of which said shift rail forms a part. Hence 120 the color-controlling arm 40 is swung bodily up and down about the axis 13 of the case-shift frame, simultaneously with the up and down movements of the platen 5. At Fig. 8 the bars are seen in printing position when 125 writing black in upper case, and in Fig. 11 when writing red in upper case. It will be understood that while the platen 5 is in its upper case position, the keys 52, 53 may be manipulated for bringing either ribbon 130

stripe into use; and also that when the color-controlling devices remain set for either color, the platen-shifting mechanism may be manipulated to shift the platen up and down; the slot 58 in the arm 59 (Fig. 5) permitting these various relations of the parts.

The vertical slot 29 in the actuator 28 may be suitably shaped for the purposes herein set forth; as for instance its upper end may be set forwardly a little, as at 66, in order to bring the ribbon carrier 36 to the correct normal position when capital letters are being written, and the lower or red stripe of the ribbon is being used. This, or other suitable shape of the slot 29, may be called for because the slot itself is not struck on an arc with the pivot 42 of the color-controlling arm as a center. During any movement of said color-controlling arm, there is some independent vibration of the lever 31, 33 about its pivot 32, because its wrist 30 is guided in a path which is not concentric with 42. This slight vibration of 31, 33 is increased by means of the off-set portion 66 on the slot, and this tends to draw down the ribbon vibrating arm 35, which otherwise might rise too high when the platen-shift rail 17 is being raised, with the color-controlling arm 40 shifted up to red position, (Fig. 11).

It will also be noticed, that owing to the fact that the vertical slot 29 diverges from an arc drawn about the axis 42 as a center, there is sufficient shifting of the lever 31, 33 between the Fig. 3 and Fig. 9 positions, to bring the arms 33, 34 well away from the Fig. 3 position, so that the same length of stroke of the arm 33 may impart a greater stroke to the ribbon-vibrating lever 35. The linkage, comprising 33, 34, and 35, is so constructed that uniform movements of the arm 33 produce, at Figs. 3 and 6, shorter strokes of the ribbon-vibrating lever 35 than is the case at Figs. 9 and 10. It will be understood, also, that substantially the same results occur when the parts are shifted to upper-case position. Thus, while all the parts always remain connected, there is still a difference in the length of the stroke in favor of the black or upper stripe of the ribbon, which is the one most used. Since no part has to be disconnected from the others, a closer fit of the various working joints can be secured and maintained, thus insuring accuracy of movement of the ribbon, besides giving the advantage of short strokes for the black stripe, and the further advantage of preventing overthrow when making such short strokes.

If desired, a stop 67, Fig. 11, may be fixed upon the machine frame to be engaged by pin 37, for arresting the ribbon-vibrator at the conclusion of its printing stroke, when writing red in the upper-case position. By

means of the stops 67 and 43 and the toggle-lock action at Figs. 6 and 8, overthrow of the ribbon in the four printing positions thereof may be practically eliminated.

Any suitable means may be provided for preventing the ribbon from covering the printing point at the type-strokes, for the purpose of making stencils; and I give for illustration a means whereby the entire ribbon mechanism is lowered enough to prevent the ribbon from covering the printing point, even though it is vibrated at the type-strokes. The cam slot 48 in the color-controlling cam plate or slide 45 is made long enough to force down the pin 49 and the color-controlling arm 40 into positions seen in Figs. 1 and 2, in which the ribbon normally stands so far below the printing point, as seen in full lines, that the vibrating lever 35 is unable, at the type-strokes, to carry the ribbon up to cover the printing point; the extreme upper position of the ribbon being seen in dotted lines at Fig. 1, just below the printing line on the platen. At this time also, the length of stroke of the ribbon-vibrating lever 35 is somewhat further reduced; the movements of the parts 33, 34 being principally in the vicinity of the straight-line dead position in which the arm 35 is moved but very little during the usual strokes of the lever 31, 33.

The color-controlling cam plate or slide 45 may, if desired, be shifted over to the Fig. 2 position by means of the rock-shaft 55 and crank 56. However, I prefer to employ a separate finger-piece 68 (Fig. 7) for shifting the ribbon mechanism to the position at Figs. 1 and 2. This finger-piece 68 is formed upon a slide 69, which is carried upon headed studs 70 fastened in the frame of the machine; the slide having horizontal slots 71 to support it and guide it upon said studs. Provided upon the inner end of the slide 69 is a rest or abutment 72 which is engaged by the pin 64, before mentioned. When the slide 69 is in normal position, Fig. 7, the rest or abutment 72 serves as a stop to be engaged by pin 64 to arrest the cross arm 54 when the color key 52 is depressed, as at Fig. 7. When it is desired to write a stencil, the operator presses the finger-piece 68 to the right, thus withdrawing the abutment 72, to permit further movement counter-clockwise of the cross-arm 54, with its rock-shaft 55 and the crank 56 thereon, this movement being effected by an abutment or edge 74, which now engages a pin 75 on an arm 76 extending down from the forward part of said rock-shaft 55 (Fig. 3), and swings the rock-shaft to the extreme position of Fig. 2, thus carrying the color-controlling cam plate or slide 45 to its extreme right-hand position. The spring detent 60 holds the rock-shaft 55 in this position, and preferably the slide 69 is also pro-

vided with a spring detent 77 to enter notches 78 and 79 in said slide. After writing the stencil, the operator may press the finger-piece 68 to the left, or he may depress the key 53 to bring the parts back to normal positions; the detent 77 assisting to complete the return of the slide 69.

It will be observed that in moving from the position at Fig. 9 to the position at Fig. 10, the lever arm 33 effects a long throw of ribbon vibrating arm 35, because the link 34 is about at right angles to the lever arm 33. In swinging, the color-controlling arm 40 down from the Fig. 9 position to the Fig. 3 position, the lever-arm 33 is swung forwardly to bring 33 and 34 nearer a straight line position, as at Fig. 3. Owing to this relation of the link 34 and arm 33, at Fig. 3, the vibration of arm 33 at the printing-stroke will effect less vibration of 35 than is the case when the parts move from the Fig. 9 normal position to the Fig. 10 printing position. In other words, the printing-stroke for black may be shorter than the printing-stroke for red, besides having the advantage of locking 35 against the over-throw as at Fig. 6. The described movement of the arm 33 in dropping from the Fig. 9 position to the Fig. 3 position is caused by the slot 29. This slot may be straight throughout its length and incline upwardly and forwardly, as at Fig. 1, instead of being vertical and terminating at its end in a crook as in the other figures. The incline of the slot at Fig. 1 presents an advantage, because it reduces the throw of ribbon vibrator 36 when the parts are shifted up around pivot 13 at the case shifting operation, and hence tends to make the lift of the ribbon no greater than the lift of the platen; the inclination of the slot tending to turn the lever 31, 33 counterclockwise on its own pivot 32 during the upward platen shift, thereby tending to draw down the lever 35 about its own pivot 41.

Variations may be resorted to within the scope of the invention, and portions of the improvements may be used without others.

Having thus described my invention, I claim:

1. In ribbon mechanism for use with a ribbon comprising different color stripes, the combination with a ribbon carrier, a ribbon-vibrating lever and a device comprising a link and lever by which the ribbon-vibrating lever is oscillated to vibrate the ribbon between a normal position of rest and an operative position, of a controlling device or arm upon which are pivoted said levers, said controlling arm mounted to swing upwardly, and carry up said ribbon-vibrating lever and ribbon carrier, together with the ribbon, when it is desired to bring the lower stripe of the ribbon into use.

2. In a typewriting machine, the combination with a key-operated universal bar and frame, of a vertically slotted yoke fixed upon said universal bar frame, a ribbon-vibrating lever, a lever having a wrist projecting therefrom into the slot in said yoke, and a link connecting said last-named lever to the ribbon-vibrating lever, said slot in the yoke permitting the wrist to play up and down as the ribbon mechanism is shifted up and down to bring different color stripes into use.

3. In a typewriting machine, the combination with a key-operated universal bar and frame, of a vertically slotted yoke fixed upon said universal bar frame, a ribbon-vibrating lever, a lever having a wrist projecting therefrom into the slot in said yoke, a link connecting said last-named lever to the ribbon-vibrating lever, said slot in the yoke permitting the wrist to play up and down as the ribbon mechanism is shifted up and down to bring different color stripes into use, a platen, and a shift frame for shifting the platen up and down to enable different types to print, said levers mounted on said frame, and said slot in the actuator accommodating the case-shifting movement.

4. In ribbon mechanism for use with a ribbon having different color stripes, the combination with a ribbon carrier and a ribbon-vibrating lever, of an actuator for said lever, a link and lever connecting the actuator to the said ribbon-vibrating lever, the ribbon-vibrating lever and ribbon carrier shiftable up and down to bring either color stripe into operative position, and means to so change the relative position of said levers and link when the ribbon is shifted that the extent of movement of the ribbon-vibrating lever relative to that of the other lever is increased, to thereby enable the actuator to impart a greater throw to the ribbon-vibrating lever, when the parts are in position to bring the lower ribbon stripe into operation than when the upper stripe is operative, thus permitting the upper ribbon stripe to have a normal position close to the printing line so that only a short throw of the ribbon is required to cause said upper ribbon stripe to cover the printing point.

5. In ribbon mechanism for use with a ribbon having upper and lower color stripes, the combination with a carrier for said ribbon and a ribbon-vibrating lever, of an actuator, a connection between said actuator and the said vibrating lever for causing the actuator to vibrate the lever and throw the ribbon over the printing point, said lever shiftable bodily up and down to bring either the upper or lower ribbon stripe into active position, said connection being modified during the said shifting of the vibrating lever to cause the actuator to effect a wider amplitude of vibration of the said lever when the latter has been shifted to bring the lower

- ribbon stripe into activity than when the upper stripe is active, whereby the normal position of the ribbon may be a comparatively short distance below the printing line, 5 and a shorter vibration of the ribbon for both the color stripes is provided than would be required if the vibrations of the ribbon were equal for the active positions of both color stripes.
10. 6. In ribbon mechanism for use with a ribbon having different color stripes, the combination with a ribbon carrier and a ribbon-vibrating lever, of an actuator therefor, and a link and lever connecting the 15 actuator to said ribbon-vibrating lever, said link and lever arranged to swing to or near the dead center when one color stripe is in printing position, said ribbon-vibrating lever shiftable bodily to bring the other 20 color stripe into position to be vibrated by said actuator to printing position, the relation of said link and lever to the ribbon-vibrating lever and actuator being changed when said other color stripe is active to in- 25 crease the throw of the ribbon.
7. In a ribbon mechanism for use with a ribbon having different color stripes, the combination with a ribbon carrier and a ribbon-vibrating lever, of an actuator therefor, a link and lever connecting the actuator to said ribbon-vibrating lever, said link and lever arranged to swing to or near the dead center when one color stripe is in printing 30 position, said ribbon-vibrating lever shift- 35 able bodily to bring the other color stripe into position to be vibrated by said actuator to printing position, the relation of said link and lever to the ribbon-vibrating lever and actuator being changed when said other 40 color stripe is active to increase the throw of the ribbon, and a stop to limit the throw of the ribbon-vibrating lever when shifted to said last-mentioned position, said link and lever when in the dead center position serv- 45 ing as a lock to prevent the momentum of the ribbon-vibrator from carrying the ribbon too far, while said first-mentioned color is active.
8. In a typewriting machine, the combination with a key-operated universal bar, of a ribbon-vibrating lever, a ribbon carrier vibrated by said lever, operating connections between the universal bar and said lever, arranged to gradually slow down the move- 55 ment of the said lever relative to that of the universal bar during the operating stroke of said bar, whereby the ribbon is gradually brought to rest over the printing point and overthrow of the ribbon prevented, said con- 60 nections between the universal bar and the ribbon-vibrating lever comprising a lever actuated by the universal bar, a link connecting said last-mentioned lever with the said ribbon-vibrating lever, said link being
- brought substantially into line with the arm 65 of said second-mentioned lever to which it is pivoted, as the ribbon-vibrating lever completes its forward throw, and means to shift the ribbon carrier and ribbon-vibrating lever bodily relatively to the second-mentioned lever, and thereby cause a different portion of the ribbon to be brought over the printing point. 70
9. In ribbon mechanism for use with a ribbon having upper and lower color stripes, the combination with a ribbon carrier, of a ribbon-vibrating lever, an actuator by which said lever is operated, a controlling device or arm upon which is pivoted said ribbon-vibrating lever, said controlling arm mounted to swing upwardly and carry up the ribbon-vibrating lever when it is desired to bring the lower stripe of the ribbon into use, and means to change the relation of said actuator and ribbon-vibrating lever during 85 the shifting of said arm whereby a greater throw of the ribbon is effected when said arm is in position to bring the lower stripe of the ribbon into use. 90
10. In a typewriting machine, the combination with a key-operated universal bar, of a slotted yoke on said bar, a ribbon-vibrating lever, a link and lever connected thereto, a platen shifting frame, and an arm mounted to swing on said frame, said levers pivoted on said arm to swing therewith and bring either color stripe of a bichrome ribbon to active position, said second-mentioned lever having a wrist to engage with the slot in said yoke, said slot operating when said 100 arm is swung to change the relation of said levers and thereby vary the extent of the throw of the ribbon by the vibrating lever. 105
11. In a typewriting machine, the combination with a ribbon-vibrator for vibrat- 110 ing a ribbon over the printing point, of a key-operated actuator to actuate said vibrator, and means for shifting said vibrator and thereby carrying the ribbon to such position that the vibration of the ribbon-vibrator by the actuator will not move the ribbon to position to cover the printing point. 115
12. In a typewriting machine, the combination with a ribbon-vibrating lever, of a key-operated actuator connected to such lever to vibrate the latter and carry the ribbon over the printing point when the keys are actuated, means forming a driving connection between said actuator and lever, means to shift the lever downwardly without interrupting said connection to such position that the vibration of the lever will not carry the ribbon up to the printing point. 120
13. In a typewriting machine, the combination with a key-operated universal bar, of a ribbon vibrator, a driving connection between the universal bar and said vibrator. 125

for vibrating the latter to vibrate the ribbon over the printing point, and a device for shifting the vibrator downwardly and simultaneously shifting said driving connection

5 to cause the ribbon vibrator to have a shorter throw when actuated by the universal bar, and thereby prevent the ribbon from being vibrated over the printing point.

14. In a typewriting machine, the combination with a ribbon vibrator, of an actuator connected to operate the vibrator and move a ribbon to printing position, and means for shifting said vibrator and concomitantly modifying said connection to 15 reduce the amplitude of vibration of said vibrator and thereby prevent the actuator from causing the ribbon to move to printing position.

15. In a typewriting machine, the combination with a ribbon carrier and a ribbon-vibrating lever to vibrate a ribbon over the printing point, of an actuator for said lever, a lever and link connecting said actuator with the ribbon-vibrating lever, and a carrier on which said levers are mounted, said carrier being shiftable downwardly to carry the ribbon to such position that when vibrated by said actuator it will not be carried over the printing point.

16. In a typewriting machine, the combination with a ribbon carrier and a ribbon-vibrating lever to vibrate a ribbon over the printing point, of an actuator for said lever, a lever and link connecting said actuator with the ribbon-vibrating lever, and a carrier on which said levers are mounted, said carrier being shiftable downwardly to carry the ribbon to such position that when vibrated by said actuator it will not be carried over the printing point, said second-mentioned lever having a slot and pin connection with the actuator arranged to shift the position of said lever relatively to the ribbon-vibrating lever when said carrier is 45 shifted downwardly, and thereby reduce the amplitude of vibration of the ribbon when the parts are shifted to non-printing position.

17. In a typewriting machine, the combination with ribbon-vibrating mechanism for use with a ribbon having upper and lower color bands, said mechanism comprising a ribbon-vibrating lever, a slotted actuator, a lever having a wrist slidale in said slot to permit the lever to be shifted, a link connecting said levers, and a shifting device on which said levers are mounted, said actuator operable through said levers when said shifting device is in an intermediate position to vibrate the ribbon and carry the upper color band over the printing point, and operable when shifted upwardly from said intermediate position to cause the lower color band to be vibrated over the printing

65 point, and operable when shifted downwardly from said intermediate position to cause the ribbon to be vibrated without covering the printing point.

18. In a typewriting machine, the combination with ribbon-vibrating mechanism for use with a ribbon having upper and lower color bands, said mechanism comprising a ribbon-vibrating lever, a slotted actuator, a lever having a wrist slidale in said slot to permit the lever to be shifted, a link connecting said levers, and a shifting carrier on which said levers are mounted, said actuator operable through said levers when said shifting device is in an intermediate position to vibrate the ribbon and carry the 80 upper color band over the printing point, and operable when shifted upwardly from said intermediate position to cause the lower color band to be vibrated over the printing point, and operable when shifted 85 downwardly from said intermediate position to cause the ribbon to be vibrated without covering the printing point, said slot formed to change the relation of the said levers and link when said carrier is shifted 90 to the upper position and thereby increase the amplitude of vibration of the ribbon, and when said carrier is shifted downwardly from the intermediate position to decrease the amplitude of the vibration of 95 the ribbon.

19. In a typewriting machine, the combination with a universal bar, of a slotted yoke carried thereby, a lever having a wrist guided in said slot, a ribbon-vibrating lever, 100 a link connecting said levers, a carrier on which said levers are pivoted, and means for shifting said carrier up and down.

20. In a typewriting machine, the combination with a universal bar, of a slotted yoke carried thereby, a lever having a wrist guided in said slot, a ribbon-vibrating lever, a link connecting said levers, a carrier on which said levers are pivoted, a platen shifting frame on which said carrier is mounted, 110 said carrier shiftable up and down with said frame to maintain an operative relation between the ribbon and platen as the latter is shifted up and down, and means to shift said carrier up and down on said 115 shifting frame to vary the position of the ribbon relatively to the platen and thereby bring different color zones of the ribbon into operation.

21. In a typewriting machine, the combination with a platen-shifting frame, of a ribbon vibrator, an actuator therefor, a swinging support or arm on which the vibrator is mounted, a vertically slotted guide plate on said shifting frame in 125 which said arm is guided in its swinging movement, a slide mounted on the shifting frame and provided with a cam slot by

which said arm is shifted up and down to shift the ribbon vibrator and thereby bring different color bands of the ribbon into active position, and means to cause a greater throw of the ribbon vibrator by said actuator when one color band is active than when the other color band is active.

22. In a typewriting machine, the combination with a platen shifting frame, of a ribbon vibrator, a swinging support or arm on which the vibrator is mounted, a vertically slotted guide plate on said shifting frame in which said arm is guided in its swinging movement, a slide mounted on the shifting frame and provided with a cam slot by which said arm is shifted up and down to shift the ribbon vibrator and thereby bring different color bands of the ribbon into active position, a key-actuated rock shaft, and an arm on said shaft having a vertical slot and pin connection with said slide to actuate the slide, said slot and pin connection permitting the slide to move bodily up and down with the platen shifting frame.

23. In ribbon shifting mechanism for use with a bichrome ribbon, the combination with a ribbon guide and ribbon-vibrating mechanism therefor, of a shifting device for shifting said mechanism to bring either color stripe of the ribbon into activity, a key-operated rock shaft for actuating said shifting device, a stop to prevent said shaft from being rocked beyond its normal range of movement, a finger-piece connected to said stop for moving the latter to inoperative position, and means operated by said finger-piece to rock said shaft beyond its normal position and thereby operate said shifting device into position to cause the ribbon-vibrating mechanism to be silenced or moved to ineffective position.

24. In ribbon mechanism for typewriting machines, the combination with a ribbon-vibrator, of an actuator therefor, shifting means for bringing either stripe of a bichrome ribbon into activity, said means comprising a key-operated rock shaft, a stop to limit the rocking movement of said shaft and thereby preventing the ribbon mechanism from being shifted to inoperative position, a manually operated carrier for said stop, and means between said carrier and the rock shaft whereby when said carrier is operated, the stop is moved to inoperative position and the rock shaft rocked to position to silence the ribbon-vibrating mechanism.

25. In a typewriting machine, the combination with a universal bar, of a ribbon-vibrator shifttable bodily to two printing positions, and having a longer printing stroke for the unusual color than for the usual color, the shorter stroke of the ribbon vibrator comprising a lock to prevent overthrow

of the ribbon, and a stop being also provided to prevent overthrow at the long stroke of the ribbon.

26. In a typewriting machine, the combination with a universal bar, of a ribbon-vibrator shifttable bodily to two printing positions, and having a longer printing stroke for the unusual color than for the usual color, the shorter stroke of the ribbon-vibrator comprising a lock to prevent overthrow of the ribbon, a stop being also provided to prevent overthrow at the long stroke of the ribbon, said ribbon vibrator being mounted for bodily case-shifting movement, and an additional stop being provided for arresting the ribbon at the conclusion of the long stroke at the time that the ribbon is in its upper case shift position.

27. In a ribbon mechanism for use with a ribbon comprising different color stripes, the combination with a ribbon-vibrating lever and an actuator therefor, of a link and lever connecting the actuator to said ribbon-vibrating lever, a support on which are pivoted the said ribbon-vibrating lever and connecting lever, said link and connecting lever arranged to swing about to dead center when the ribbon is thrown to printing position, to thereby serve as a lock to prevent the momentum of the ribbon vibrator from carrying the ribbon too far, said support shifttable to bring a different stripe into use, and means whereby the relative position of the said link and lever is changed as the support is shifted, to thereby vary the throw of the ribbon effected by the actuator.

28. In a typewriting machine, the combination with a key-operated universal bar, of a ribbon-vibrating lever, a ribbon carrier vibrated by the lever, and operating connections between the universal bar and said lever, the said connections comprising an interponent lever actuated by the universal bar, and a link pivoted to said levers to transmit motion from said interponent lever to the ribbon-vibrating lever, the interponent lever being so arranged that its direction of movement at the point thereof at which the power is applied to said link gradually changes to a direction substantially perpendicular to the direction in which the power is applied by the link to the ribbon-vibrating lever, so that during the operating stroke of the universal bar the ribbon is gradually brought to rest over the printing point, and overthrow of the ribbon is prevented.

29. In a typewriting machine, the combination with a universal bar, of a ribbon vibrator for vibrating a color for usual use and a color for unusual use, said vibrator shifttable bodily to set it at two printing positions from which it is vibratable for printing with said colors respectively, and motion-transmitting means forming a connec-

tion between the universal bar and said vibrator, said means arranged to cause a longer printing stroke of the vibrator by the universal bar when the vibrator is set for printing with the unusual color than when set for printing with the usual color.

30. In a typewriting machine, the combination with a universal bar, of a ribbon vibrator for vibrating a color for usual use and a color for unusual use, said vibrator shiftable bodily to set it at two printing positions from which it is vibratable for printing with said colors respectively, and motion-transmitting means forming a connection between the universal bar and said vibrator, said means arranged to cause a longer printing stroke of the vibrator by the universal bar when the vibrator is set for printing with the unusual color than when set for printing with the usual color; said ribbon vibrator also shiftable bodily to a third position, said motion-transmitting means arranged to produce a still shorter stroke of the vibrator when vibrated from said third position.

31. In a typewriting machine, the combination with a universal bar, of a ribbon vibrator for vibrating a color for usual use and a color for unusual use, said vibrator shiftable bodily to set it at two printing positions from which it is vibratable for printing with said colors respectively, and motion-transmitting means forming a connection between the universal bar and said vibrator, said means arranged to cause a longer printing stroke of the vibrator by the universal bar when the vibrator is set for printing with the unusual color than when set for printing with the usual color; said ribbon vibrator also shiftable bodily to a third position, said motion-transmitting means arranged to produce a still shorter stroke of the vibrator when vibrated from said third position, the length of throw of the vibrator while operating from said third position being such that the ribbon will vibrate idly and not cover the printing point at the type-strokes.

32. In a typewriting machine, the combination with a universal bar, of a ribbon vibrator for vibrating a color for usual use and a color for unusual use, said vibrator shiftable bodily to set it at two printing positions from which it is vibrated for printing with said colors, respectively, and motion-transmitting means forming a connection between the universal bar and said vibrator, said means arranged to cause a longer printing stroke of the vibrator by the universal bar when the vibrator is set for printing with the unusual color than when set for printing with the usual color, said motion-transmitting means comprising a lock to limit the throw of the vibrator and prevent overthrow of the ribbon.

33. In ribbon mechanism for use with a ribbon comprising different color stripes, the

combination with a ribbon-carrier, a ribbon-vibrating lever, and a device by which said lever is oscillated, of a support upon which are mounted said ribbon-vibrating lever and said lever-oscillating device, said support shiftable upwardly to carry said ribbon-vibrating lever and ribbon-carrier together with the ribbon when it is desired to bring the lower stripe of the ribbon into use, and means to vary the relation of the ribbon-vibrating lever to the said oscillating device as the support moves upwardly, so that the throw of the ribbon-vibrating lever is greater when said support is in its upper position.

34. In a typewriting machine, the combination with a key-operated universal bar and frame, of a ribbon-vibrating lever, a lever having a shiftable connection with the universal bar frame, and a link connecting said last-named lever to the ribbon-vibrating lever, said levers, link and ribbon being shiftable up and down to bring different color stripes into use, said shiftable connection arranged to vary the relation of said levers and link as they are shifted up and down so that the length of throw of the ribbon-vibrating lever is different for different color stripes.

35. In a typewriting machine, the combination with a ribbon vibrator for vibrating a ribbon over the printing point, of a key-operated actuator to actuate said vibrator, and means for shifting said vibrator and concomitantly varying the relation of the actuator to the vibrator, so that the ribbon is carried away from the printing point and its amplitude of vibration so reduced that the vibration of the vibrator by the actuator will not move the ribbon to position to cover the printing point.

36. In a typewriting machine, the combination with a ribbon vibrator for vibrating a ribbon over the printing point, of a key-operated actuating device, means for transmitting motion from said device to the ribbon vibrator for actuating the latter, said transmitting means comprising a lever and link connected to the ribbon vibrator, and means for shifting the ribbon vibrator to carry the ribbon away from the printing point and simultaneously vary the relative position of the link and actuating lever to reduce the throw of the ribbon, so that the vibration of the ribbon vibrator by the actuator will not move the ribbon vibrator to position to cover the printing point.

37. In a typewriting machine, the combination with a universal bar, of a ribbon vibrator for vibrating a ribbon having a color stripe for usual use and a color stripe for unusual use, said vibrator shiftable bodily to set it at two printing positions from which it is vibratable for printing with said color stripes, respectively, motion-transmitting means forming a connection between the

universal bar and said vibrator, said means arranged to cause a longer printing stroke of the vibrator by the universal bar when the vibrator is set for printing with the unusual color stripe than when set for printing with the usual color stripe, said motion-transmitting means arranged to form a lock to prevent overthrow of the ribbon when the usual color stripe is in use, and a stop to prevent overthrow at the longer printing stroke of the vibrator.

38. In a typewriting machine, the combination with a universal bar, of a ribbon vibrator for vibrating a ribbon having upper and lower color stripes, said vibrator shiftable bodily to set it at two printing positions from which it is vibratable for printing with said color stripes respectively, motion-transmitting means forming a connection between the universal bar and the vibrator, said means arranged to cause a longer printing stroke of the vibrator by the universal bar when the vibrator is set for printing with the lower color stripe than when set for printing with the upper color stripe, said ribbon vibrator being mounted for bodily case-shifting movement in addition to said first-mentioned movement thereof, said motion-transmitting means arranged to form a lock to prevent overthrow of the ribbon when the upper color stripe is in use, a stop to prevent overthrow of the ribbon when the lower color stripe is in use in one case position, and an additional stop to prevent overthrow of the ribbon when the lower color stripe is in use in the other case position.

39. In a typewriting machine, the combination with a universal bar, of a slotted yoke carried thereby, a lever having a wrist guided in said slot, a ribbon-vibrating lever, a link connecting said levers, a carrier on which said levers are mounted, a platen-shifting frame shiftable to different case positions, means for causing the said carrier to shift when said frame is shifted, and means to shift the carrier while said frame is at rest.

40. In a typewriting machine, the combination with a universal bar, of a slotted yoke carried thereby, a lever having a wrist guided in said slot, a ribbon-vibrating lever, a link connecting said levers, a carrier on which said levers are mounted, a platen-shifting frame shiftable to different case positions, and a key-actuated device for shifting said carrier to bring different color stripes of a ribbon into use, said shifting device forming a connection between the carrier and the platen-shifting frame for causing the carrier to shift with said frame and maintain an operative relation between the platen and ribbon in the different case positions.

41. In a typewriting machine, the combi-

nation with a platen shiftable to upper and lower case positions, of a ribbon-vibrating lever for vibrating a ribbon having different color zones or stripes, a device by which said lever is operated, a universal bar to actuate said operating device and move the ribbon over the printing point on the platen, a support for said lever and its operating device, a key-operated shifter for shifting said support and thereby shifting said lever and operating device up and down to bring either color stripe into active position, means to vary the relation of the said operating device to the ribbon-vibrating lever during the shifting of said support and thereby vary the amplitude of vibration for the different color stripes, and means forming a connection between said shifter and the platen for causing said shifter to move the ribbon-vibrating lever and its operating device up and down as the platen is shifted up and down and thereby maintain an operative relation between the ribbon and the platen as the latter is shifted.

42. In a typewriting machine, the combination with a carriage, a platen thereon, and means comprising a shift rail for shifting the carriage to upper and lower case positions, of a ribbon carrier, a ribbon-vibrating lever, a universal bar, a lever and link forming an operating connection between the universal bar and the ribbon-vibrating lever, a support on which said levers are mounted, a shifter connected to said support and operable to move the latter to thereby shift said levers and bring either color stripe of a bichrome ribbon into operative position, a connection between said shifter and the carriage shift rail for moving said shifter and support up and down as the platen moves up and down, and a key for operating the shifter.

43. In a typewriting machine, the combination with a shift rail, of a platen supported thereon and movable therewith to upper and lower case positions, a ribbon carrier for a bichrome ribbon, a ribbon-vibrating lever, means comprising a lever and link connecting said levers for actuating the ribbon-vibrating lever, a support for said levers, a bracket on said shift rail, and a shifting device having a slot-and-pin connection with said support to permit an up and down movement of the support relative to the shift rail, and a shifting device having a slot-and-pin connection with said bracket, permitting a horizontal movement of the shifting device and causing the latter to be moved up and down with the shift rail, said shifting device comprising a cam operable to shift said support vertically when the shifting device is moved horizontally.

44. In a ribbon mechanism for typewriting machines, the combination with a universal bar, of a ribbon carrier, a ribbon-vi-

brating lever, a lever operated by the universal bar, a link connecting said levers, a support on which the ribbon-vibrating lever is pivoted, a shifting device having an inclined slot-and-pin connection with said support for moving the latter up and down, when the shifting device is moved trans-

versely, and key-operated means for causing said movement of the shifting device.
